UNITED STATES PATENT OFFICE.

FREDRICH J. RODE, OF CHICAGO, ILLINOIS, ASSIGNOR TO MARQUETTE TOOL & MFG. COMPANY, OF CHICAGO, ILLINOIS, A CORPORATION OF ILLINOIS.

SHEET-METAL-WORKING MACHINE.

Application filed July 23, 1926. Serial No. 124,897.

This invention relates to improvements in sheet metal working machines, and one of the objects of the invention is to provide an improved sheet metal drawing machine embodying a fluid pressure cushion for the blank holding means and which cushion is adapted to be removed or swung out of the way to permit of the use of the same machine for blanking operations, thereby rendering it possible to convert the same machine from a drawing press to a blanking press and vice versa.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which—

Figure 1 is a view partly in side elevation, partly broken away and partly in section of a sheet metal working machine having a cushion attachment constructed in accordance with the principles of this invention applied thereto, and showing the cushion in position so that the machine may be used as a drawing machine.

Figure 2 is a view similar to Figure 1, showing the cushion rendered inactive and swung out of the way, and the press converted into a punching press.

Figure 3 is a left hand end elevation of the lower portion of Figure 1.

Figure 4 is a sectional view taken on line 4-4, Figure 1.

In the drawings the numeral 10 designates a supporting base of any desired configuration and 11 an upright standard, which, in the present form of the invention is pivotally mounted as at 12 to the base, so that the standard may be adjusted to any desired angle of inclination with respect to the base.

Carried by the standard is a base plate 13 upon which may be mounted a suitable die member 14.

A reciprocable die member 15 connected with the reciprocating member or ram 16 is

also mounted upon the standard and the ram or member 16 is adapted to be reciprocated in any well known manner (not shown).

A blank holding member 17 is provided which encompasses the die 14 and co-operates with the die 15 for clamping the material 18 therebetween during the forming of the material over the die 14 while the ram 16 descends.

The blank holding member 17 is supported by means of pins 19 which pass through the bed plate 13, and these pins engage or rest upon a pin plate or pad 20 which is connected with the piston rod 21, which in turn is connected with a piston (not shown) that is reciprocable in a cylinder 22.

The cylinder 22 is supported by a member 23 preferably in the form of a bracket or support pivotally mounted as at 24 upon a portion of the standard 11. The bracket or support 23 is held in position so that the cushion will be operative with respect to the blank holding member 17, in any desired or suitable manner such as by means of bars or rods 25 which depend from a portion of the standard 11. The support 23 is preferably provided with recesses or openings 26 which extend through the front edge of the support, and these openings 26 are positioned so as to receive a portion of the bars or rods 25. Nuts 27-28 are threaded upon the bars 25 respectively above and below the support 23 for holding the latter in position, and if desired plates or closure members 29 may be removably secured to the edge of the support 23 for holding the parts against accidental disengagement.

Depending from the cylinder 22 is a tubular member 30 which has communication with the interior of the cylinder and connected with this member 30 is a supply pipe 31 which leads to any suitable source of fluid supply (not shown).

A drain cock 32 may be provided, if desired, and is connected with the tubular member 30.

When the parts are in the position shown in Figure 1, the cushion will be rendered active with respect to the blank holding

member 17 so that when the die 15 descends it will contact with the work 18 and the work will then be clamped between the die 15 and the blank holding member 17. During a further descending movement of the ram 16 and die 15 the blank will be formed over the die 14 as the blank holding member 17 will be depressed against the resistance of the cushion formed by the cylinder 22, the piston therein (not shown) and the piston rod, fluid being supplied to the under side of the piston from any suitable source.

When it is desired to convert the machine from a drawing press into a blanking or 15 punching press, the cushion is rendered inactive and this is accomplished by allowing the fluid in the cylinder to escape so that the pin plate or pad 20 will drop to the position shown in dotted lines in Figure 1. The nuts 20 28 may then be adjusted or removed and the plates 29 detached so that the support 23 will swing about its pivot 24 from the position shown in full lines in Figure 1 to the position shown in Figure 2.

25 The plate 13 with the die 14 thereon, together with the blank holding member 17 and pins 19 may be removed and another plate 33 may be placed upon the bed 34 of the machine. The plate 33 is provided with 30 an aperture 35 therethrough, and a die 36 having an aperture 37 therethrough is mounted upon the plate 33 and secured in position in any suitable manner.

The die 15 is also removed and another 35 die 38 of the desired configuration may be attached to the ram or reciprocating member 16.

The press will then be converted into a 40 punching or blanking press and as the member 16 is reciprocated the die 38 will co-operate with the die 36 to punch the material 49 which is held in position upon the top of the die 36.

The punchings 40 from the material 39 45 will then fall through the opening 35 in the plate 33, the cushion during this operation being out of the way so as not to impair the operation of the machine as a punching or blanking machine.

50 If desired, and as a means for insuring the holding of the cushion out of the way and in an inoperative position, any suitable means may be provided. A simple and efficient means embodies an eye 41 which is connected with the support 33, and a hook 42 is connected by one end as at 43 with the standard 11. This hook is adapted to engage in the eye 41 and thereby hold the support 23 with the cylinder 22 thereon in 60 the position shown in Figure 2.

With this improved construction it will be manifest that there is provided a simple and efficient means whereby a single machine may be operated as a shaping or a punching 65 or a blanking machine, thereby increasing

the efficiency of the machine, with the result that one machine only is necessary to perform operations of entirely different characters.

While the preferred form of the invention 70 has been herein shown and described, it is to be understood that various changes may be made in the details of construction and in the combination and arrangement of the several parts, within the scope of the claims, 75 without departing from the spirit of this invention.

What is claimed as new is:—

1. A sheet metal drawing press embodying blank holding means, a reciprocable member with which the blank holding means co-operates to grip the work, cushioning means for the blank holding means, means embodying a pivotal connection between the press and cushion for rendering the cushioning means inactive, and means for converting the said drawing press into a blanking or punching press when the said cushioning means is rendered inactive. 80

2. A sheet metal drawing press embodying blank holding means, a reciprocable member with which the blank holding means co-operates to grip the work, cushioning means for the blank holding means, and means swingingly mounting the said cushioning means for adjustment to a position out of the way to permit another and different character of operation to be performed by the said reciprocable member. 90

3. A sheet metal drawing press embodying blank holding means, a reciprocable member with which the blank holding means co-operates to grip the work, a fluid pressure cushion for the blank holding means, and means embodying a pivotal connection between the cushion and press for mounting the said cushioning means for bodily adjustment to a position out of the way to permit another and different character of operation to be performed by the said reciprocable member. 100

4. A sheet metal drawing press embodying upper and lower co-operating die members, blank holding means co-operating with one of the die members for clamping the work while it is being shaped, a cushion for the blank holding means, means mounting the cushion for bodily swinging movement whereby the cushion may be swung into an inoperative position with respect to the shaping dies, and an interchangeable die for one of the first said dies for converting the press from a drawing press into a blanking or punching press. 115

5. A sheet metal drawing press embodying upper and lower co-operating die members, blank holding means co-operating with one of the die members for clamping the work while it is being shaped, a fluid pressure cushion for the blank holding means, 120

means mounting the cushion for bodily swinging movement whereby the cushion may be swung into an inoperative position with respect to the shaping dies, and an interchangeable die for one of the first said dies for converting the press from a drawing press into a blanking or punching press.

5 6. A sheet metal drawing press embodying a base, a die supported thereby, a reciprocable member, a die carried by the said member and co-operating with the first said die, a swinging support, a cushioning device carried by the support and adapted to be positioned beneath one of said dies, blank holding means upon which the said cushion operates, the said cushion being movable with the said support into an inactive position while the remaining portions of the machine remain active.

10 7. A sheet metal drawing press embodying co-operating dies between which the material is worked, and means embodying a swingingly mounted cushioning device shiftable to another position upon the press, and interchangeable dies for converting the said machine from a sheet metal drawing press into a sheet metal punching or blanking machine.

15 8. A sheet metal drawing press embodying co-operating dies between which the material is worked, and means embodying a cushioning device and interchangeable dies for converting the said machine from a sheet metal drawing press into a sheet metal punching or blanking machine, the said cushioning device embodying a cylinder and piston, and a swinging support upon which the said cylinder is mounted.

20 9. A sheet metal drawing press embodying a bed plate, a ram member reciprocable thereabove, a swingingly mounted support disposed below the said bed plate, a die cushion mounted upon the support and movable therewith, the said support being adapted to be moved about its pivot to swing the said cushion into an inactive position and out of the way, and means for securing the support against movement about its pivot.

25 10. A sheet metal drawing press embodying a bed plate, a ram member reciprocable thereabove, a swingingly mounted support disposed below the said bed plate, a die cushion mounted upon the support and movable therewith, the said support being adapted to be moved about its pivot to swing the said cushion into an inactive position and out of the way, means for securing the support against movement about its pivot, and

30 60 means for supplying pressure fluid to the cushion.

11. A sheet metal drawing press embodying a bed plate, a ram member reciprocable thereabove, a swingingly mounted support disposed below the said bed plate, a die

cushion mounted upon the support and movable therewith, the said support being adapted to be moved about its pivot to swing the said cushion into an inactive position and out of the way, means for securing the support against movement about its pivot, and interchangeable die members for converting the press from a drawing into a blanking press.

70 12. A sheet metal working press embodying a plurality of pairs of interchangeable co-operating dies, a reciprocable ram to which one of the dies of the respective pairs is secured, and a swingingly supported cushioning device adapted to be rendered active with respect to one of said pairs of dies and to be shifted to another position upon the press to render the same inactive with respect to another of the pairs of said dies whereby work of two different characters

be interchanged with other dies for a different metal operation, a cushioning device mounted upon the said press, the weight of the said cushioning device being at all times sustained by the press, and means adapting the cushioning device to be shifted upon the press into an active and inactive position

with respect to the dies and while the weight of the cushion is sustained by the press.

In testimony whereof I have signed my name to this specification, on this 21st day of July, A. D. 1926.

FREDRICH J. RODE.
